UNITED STATES PATENT OFFICE.

GEORGE MANIERRE, OF MILWAUKEE, WISCONSIN.

LOADER AND UNLOADER FOR RAILROAD CARS.

Application filed April 23, 1921. Serial No. 463,758.

To all whom it may concern:

Be it known that I, GEORGE MANIERRE, a citizen of the United States, residing at Milwaukee, county of Milwaukee, and State of Wisconsin, have invented a new and useful Improvement in Loaders and Unloaders for Railroad Cars, of which the following is a specification.

This invention relates to improvements in loaders and unloaders for railroad cars, or the like.

It is an object of the invention to provide a device of this character which can readily be transported to the vehicle or vessel to be unloaded or loaded, instead of requiring that the vehicle or vessel should be moved to a definite place at which the loader is stationarily mounted.

It is an object of the invention also to provide a device of this character in which a conveying mechanism, as for instance, an endless belt, is situated on the loader and actuated for moving the goods to a discharge position, so as to facilitate the emptying of the car or vessel, or to load the car or vessel, respectively.

It is also an object of the invention to provide adjustable means for tensioning the loader or unloader and for directing the discharge of the goods carried by the conveyor to the discharge position.

It is also an object of the invention to combine with the endless conveyor a chute or the like through which the conveyor is guided and which is mounted on a transportable frame, carrying the prime mover of the conveyor for the object of creating a transportable self contained unit through which the loading or unloading may be rapidly effected, and which after the completion of the loading or unloading of one vehicle may rapidly be moved to another position.

With these and numerous other objects in view, an embodiment of the invention is described in the following specification and is illustrated in the accompanying drawings.

In the drawing:

Fig. 1 is a side elevation of the entire apparatus,

Fig. 2 is a longitudinal central section through the principal parts, on a large scale,

Fig. 3 is a top plan view of a portion of the conveyor and its adjusting means, 55

Fig. 4 is a sectional view on lines 4—4 of Fig. 1,

Figs. 5, 6, 7, and 8 are sectional views on lines 5—5, 6—6, 7—7, and 8—8 respectively, of Fig. 1, and 60

Fig. 9 is a top plan view of the front portion of the device.

The sub-structure of the transportable plant comprises a truck, having a platform 1 with relatively large rear wheels 2, and one or more relatively small wheels or rollers 3, which are mounted so as to facilitate the steering of this truck. A chute 4, including the side plates 5, and the bottom member 6, is carried by this sub-structure 70 through a plurality of braces or supports indicated at 8, 9 and 10, which may again be reinforced by transverse elements 11 and 12. The members 8, 9, and 10 are secured at their bottom ends to suitable gusset plates 75 13 and 14, respectively, and at their top ends the members 9 and 10 are fixed to a block 15 which is rigidly secured to the chute 4. The other bracing members 8 have their top ends fastened to a similar attachment piece 80 16, and handles 17 mounted on the braces 8 will facilitate the conveyance of the entire device from one place to another.

The chute serves for receiving a portion of an endless conveyor 20, which includes 85 a flexible belt 21 provided with a number of transverse bars or rods 22, spaced longitudinally of the belt and securely fastened to the outer surface of the same. Figs. 4 to 8 show that there are always two of these 90 bars 22 on the same transverse line, but separated from each other near the longitudinal axis of the belt. Owing to this arrangement the flexibility of the belt transversely of its axis is maintained in spite of 95 the transverse reinforcing bars, which at the same time aid materially in the conveyance of the goods.

An extension 23 near the forward end of the chute is constructed as a charging 100 trough. It has a slanting front wall 24 which is reinforced by bars 25, and the lateral walls of this extension are secured to the lateral walls 5 of the chute by an angle plate 26. The lower portion of the front wall 23, is rounded towards the lateral

walls of the chute, as indicated at 28 in Fig. 9, to direct the material charged uniformly towards the conveyor 20, the latter passing through the front of the chute 4, 5 by a slot 30, provided in the lower end of the front wall 24 of the extension.

The drive of the conveyor is effected by a motor 31 which is enclosed in a housing or casing 32, mounted on the platform 1 of the truck and which drives through a suitable link chain, 33, a sprocket wheel 34. This wheel is mounted on a shaft 35, which is carried in brackets 36, on the bracing elements 10, near the end of the structure. 15 The shaft 35 to which the sprocket 34 is fixedly secured, also serves for supporting the hub parts 37 of a pulley 38, Fig. 8, over which the conveyor 20 is trained. The hub sleeves 37 are keyed to the shaft 35 and 20 are united with the wooden pulley or roller 38 by means of suitable fasteners. The ends of the shaft 35 are rotatably mounted in bearings of brackets 36, and in this way the shaft will impart the necessary movement to the belt 21 through the pulley 38. Near the opposite end of the chute 4 the lateral walls are extended downwardly as indicated at 39, Fig. 1, and a bracket 40 is mounted on each extension, these extensions 25 being provided with slots (not shown) to permit of longitudinal adjustment of the brackets. The bearing brackets 40 support below the chute the shaft 41 by means of sleeves. Roller bearings 42 are united with 30 a pulley 43, over which the conveyor is trained. A tensioning device for maintaining the conveyor taut, so as to prevent excessive sag between the turning points, includes lugs 45, Fig. 3 which are secured to 35 the lateral walls of the chute 4 and which are tapped to receive the pressure screws 46, the ends of which impinge upon the lugs 47 of the brackets 40. By this means therefore the conveyor can be adjustably tightened whenever desired without calling for an extension on the chute itself.

The material which is carried on the upper surface of the conveyor in the chute is transported in the trough upwardly and will therefore be discharged near the pulley 41. At this end of the chute a hinged cover 50 is movably secured to the conveyor chute, and is normally held in alignment with the main part of the conveyor 55 through a rod 51, which has a handle portion 52 near the charging end, and which is provided with a plurality of notches 53, near the handle portion. A small bracket 54, Fig. 6, is fastened to the cover plate 55 for the chute, and a transverse pin 56 extending through the bracket 54 is adapted to enter into locking engagement with any of the notches 53 of the rod 51. The front end of the rod 51 is pivotally secured at 60 57 to a small link 58 which is fixed to the

top of the cover 50, permitting thereby said cover to be moved about the pivot 60 which is located near the end of an arm 61, riveted or secured in some other suitable way to the lateral walls of the chute 4.

70

Owing to this arrangement the cover 50, therefore, may be raised or lowered with respect to the pulley, so as to prevent the rise of dust or the like at the turning point of the conveyor belt where the material is 75 discharged.

In the operation of conveyors of this character a considerable amount of bulk material, as for instance sand, gravel, coal, enters between the lower surface of the belt 80 21 and the chute. This material is taken along by friction, and it would gradually increase and interfere with the operation of the machine.

In order to effect a discharge of this material from the conveyor, at a point near the turning point of the same, the bottom plate of the chute 4 is provided near the pulley or roller 43 with an opening and deflecting discharge chutes 70.

90

A very large part of the material which is carried by friction between the lower surface of the belt 20 and the bottom of the chute, will therefore be discharged through the deflecting chutes 70 which are fastened to the bottom by means of the angle irons 71. From Fig. 5 it will be seen that the material which leaves the conveyor chute through the opening to drop into the deflecting chute 70 will be discharged beyond the lateral edges of the lower part of the conveyor and in proximity to that point of discharge at which the material transported on the upper surface of the conveyor is discharged.

95

While the larger part of this material will drop through the chutes 70 it may still be possible that a portion of the material will be retained between the surface of the pulley 43 and the lower surface of the conveyor belt 21. This material will then slide on the conveyor belt downwardly until it will become wedged between the lower pulley or drum 38 and the conveyor belt which is trained about the same. In order to prevent that the material again should be taken along by the friction between conveyor and chute, another discharge device is provided in close proximity to the lower or driven drum 38. This discharge device 110 as illustrated in Figs. 1, 2 and 7 comprises a bracket 73 which is connected to the braces 115 10 and which also includes two lateral deflecting chutes 74. The material compressed between the surface of the pulley 38 and the conveyor will be released of this pressure near the top of the pulley and will be thrown by the action of the conveyor into the chute 74 from which it will be discharged laterally. The entry of this material into 120 125 130

the chutes is facilitated by the provision of an angular flaring plate 75 or spout which is directed towards the drum 38.

In the operation of the device the entire machine is moved to a point adjacent the loading or unloading door of the vehicle. This movement is facilitated through the provision of the handles 17 on the braces 11 and through handle 76 at the front plate 10 24 of the chute. After having been moved into position the switch 77 for the motor 31 is closed, and the conveyor is thereby actuated. The material is moved manually or by mechanism (not shown) from pile or 15 heap into the extension 23 where it is distributed uniformly upon the adjacent part of the conveyor. The operator who preferably is stationed near the motor adjusts the handle 52 of the deflecting cover 50 so as to 20 move the cover into a more or less deflected position as indicated in Fig. 2. In this way the material while being loaded is transported to the vehicle or when the device is used for unloading the material is moved to 25 a point remote from the vehicle, and after the operation has been completed, the entire device may be moved to another place where the loading or unloading of another vehicle may be carried out.

Owing to the provision of the deflecting chutes 70 and 74 the operation of the conveyor will not be interfered with through the material which may gather between the bottom of the chute and the lower surface 30 35 of the conveyor. This material will be automatically removed at a plurality of points and the entire device therefore can readily be shifted to another point of operation.

I claim:—

1. In a device of the character described, in combination, a portable truck, a trough having a substantially continuous bottom wall and fixedly mounted upon said truck,

an endless belt conveyor operating one of its stretches in said trough, an angularly 45 variable cover section pivoted on the side walls of said trough and extending beyond one end thereof, pulleys for propelling said belt, a collecting member adjacent to one of said pulleys between the stretches of the 50 conveyor comprising inclined planes disposed transversely of the conveyor and a blade secured to said planes and projecting toward said pulley to receive material thrown therefrom.

2. In a device of the character described, the combination of a transportable sub-structure, a chute carried thereby in fixed position, a conveyor traveling within said chute, a pair of pulleys around which said 60 conveyor is trained, a deflecting cover hingedly connected with one end of the chute and adjacent one of said pulleys, a rigid tension element connected with the cover, means for locking the tension element in a plurality 65 of different positions, and means mounted on the sub-structure for actuating the conveyor.

3. In a device of the character described, in combination, a supporting truck, an end- 70 less conveyor and pulleys for propelling same, a trough extending substantially the entire length of the conveyor and supporting one of its stretches, an angularly adjustable deflecting cover having side walls hinged 75 adjacent to their ends to the side walls of said trough, and means for adjusting said deflecting cover extending over and toward the opposite end of said conveyor.

In testimony whereof, I affix my signature so in the presence of two witnesses, at 85 Oneida St., Milwaukee, Wisconsin.
